(57) **CLAIM**

The ornamental design for a knob for home appliance, as shown and described.

DESCRIPTION

FIG. 1 is a perspective view of a knob for home appliance, showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is an enlarged view of the portion identified by the dot-dot-dash line in FIG. 1;

FIG. 9 is an enlarged view of the portion identified by the dot-dot-dash line in FIG. 2;

FIG. 10 is an enlarged view of the portion identified by the dot-dot-dash line in FIG. 5; and,

FIG. 11 is a partially enlarged view of the portion 11 encircled in FIG. 7.

The broken lines are for illustrative purposes only and form no part of the claimed design.

The dot-dash broken lines encircling portions of the claimed design that are illustrated in enlargements form no part of the claimed design. The dot-dot-dash lines define boundaries of the claimed design and form no part of claimed design. The shade lines in the claimed design show contour and not surface ornamentation.
